ELECTRIC LIGHTING FIXTURE

Glenn E. MacFadden, Buffalo, N. Y., assignor to
 Markel Electric Products, Inc., Buffalo, N. Y.,
 a corporation of New York

Application March 24, 1937, Serial No. 132,797

1 Claim. (Cl. 240—128)

This invention relates to electric lighting fixtures of the kind which utilize a diffuser for modifying the light emitted by the lamp and more particularly involves improvements in the means by which the said diffuser is attached to the fixture.

One object of the invention is to provide for facility in attaching and detaching the diffuser.

A further object is to provide an electric lighting fixture which is so designed that the lamp and diffuser may be located in close proximity to the wall upon which the fixture is mounted.

A still further object is to provide a fixture which is pleasing and attractive in appearance.

15 A still further object is a fixture in which provision is made for preventing accidental release of the diffuser.

The invention is illustrated in the accompanying drawing in which:

20 Figure 1 is a section through a fixture embodying the features of the invention.

Figure 2 is a horizontal section taken along line 2—2 of Figure 1.

25 Figure 3 is a fragmentary section taken along line 3—3 of Figure 2.

The fixture, as illustrated, includes a circular holder, or pan, 5 which is adapted to be arranged over a suitable electrical outlet and which is formed with a marginal flange 6 and a central depressed body 7. The portion of the holder which connects the said flange and body provides an annular shoulder 8, the said body being formed with a central opening 9 for accommodating a threaded post 10 which is suitably anchored to the wall against which the fixture is mounted. A nut 11 which is screwed upon the post 10 cooperates with the body 7 to secure the holder against the said wall. When the holder 5 is mounted as shown the flange 6 thereof engages the wall to space the body 6 a predetermined distance from it. The wires 12 from the electrical outlet pass from under the body 7 through an opening 13 and are connected to the socket 14 of the lamp 15 of the fixture, the said socket being mounted upon the said body by a bracket 16.

40 The light emitted by the lamp 15 is modified by a diffuser 17 of glass or any other suitable translucent material. It is of the general shape of a bowl and is formed at its open end with an inwardly directed flange 17a which fits against the shoulder 8 of the holder, the said flange terminating in a neck 18 which extends into the depression delimited by the said shoulder. The diffuser is held in the position shown by clips 19. 45 The latter are diametrically opposed and are

formed or provided with legs 20 which are suitably secured to the body 7 of the holder. Each of the said clips is formed with a finger 21 which extends into the neck 18 of the diffuser, the outer end of the said finger being curved as indicated at 22 and engaging an internal shoulder 23 provided at the juncture of the flange and neck of the diffuser. The fingers 21 are parts of open resilient loops 24 which are located in openings 25 formed in the body 7 of the holder. The 10 clips 19 are so designed that the curved ends of the fingers 21 hold the diffuser firmly seated against the shoulder 8. The resiliency of the loops 24, however, enables the diffuser to be detached simply by pulling it away from its seat, 15 the fingers 21 moving toward one another as they are withdrawn from the neck of the diffuser. The attachment of the diffuser to the holder is preferably accomplished by inserting one side of the neck 18 behind the finger of one of the clips 20 before any attempt is made to insert the other side of the neck behind the finger of the other clip. Thereafter the finger of the last mentioned clip is forced inwardly far enough to permit its curved end to enter the neck of the diffuser. The 25 assembling operation is then completed by pressing the diffuser to its seated position, the curved end of the finger moving beneath the shoulder 23 during the final part of such movement to co-operate with the finger of the companion clip in 30 holding the diffuser in such position until it is again removed in the manner described. The diffuser, therefore, may be detached and attached with facility as occasion may demand. At the 35 same time its accidental release is prevented.

The fixture described is pleasing and attractive in appearance, being enhanced in these respects by the concealment of the means by which the diffuser is attached to the holder. A further advantage obtained is that the lamp and diffuser 40 may be located in close proximity to the wall upon which the fixture is mounted, the fixture in this aspect resembling and having in substantial degree the advantages of fixtures of the built-in type.

I claim as my invention:

In an electric lighting fixture, the combination of a holder which is adapted to be mounted against a wall over an electrical outlet, said holder having a body which is provided with diametrically opposed openings and being formed with a marginal flange for spacing said body from said wall, the portion of the holder connecting said body and flange providing a shoulder, a lamp, means for mounting said lamp on said body, a 50

diffuser which fits over said lamp, said diffuser being formed at its open end with an inwardly directed flange which overlies said shoulder and fingers carried by said body which extend into the open end of said diffuser to engage its flange at substantially diametrically opposed points, said

fingers being parts of resilient loops which are located in said openings and being yieldable to release said diffuser when it is pulled for the purpose described.
